ELEVATOR GATE MECHANISM

Louis H. Pranger, Racine, Wis.

Application December 13, 1930, Serial No. 502,196

21 Claims. (Cl. 187—60)

This invention relates to improvements in elevator gate mechanism and its purpose is to provide an improved device for operating the safety gates or doors which are employed to close the openings leading into an elevator shaft at the different floors of a building. The principal object of the invention is to provide an improved device by which the elevator gates or doors are automatically opened when the elevator reaches a floor and are automatically closed as the elevator leaves that floor. A further object of the invention is to provide improved gate operating mechanism adapted to be mounted in the elevator shaft and comprising parts arranged to be automatically actuated by a member carried by the elevator car so that as the car moves along the shaft in either direction, it will open the gates at a particular floor to a predetermined extent as the elevator car reaches that floor. A further object of the invention is to provide means for automatically opening the elevator safety gates at each floor of a building as the elevator car reaches each such floor in combination with means for rendering said mechanism inoperative at any particular floor, at the will of the operator. Still another object is to provide gate opening mechanism adapted to be employed with an elevator car and comprising adjustable means for varying the points at which the gates are opened and closed. Other objects of the invention relate to various features of construction and arrangement which will appear more fully hereinafter.

The nature of the invention will be understood from the following specification taken with the accompanying drawings, in which one embodiment of the invention is illustrated. In the drawings,

Fig. 1 shows a vertical section through an elevator shaft and an elevator car showing the application thereto of the present invention;

Fig. 2 shows a horizontal section on the line 2—2 of Fig. 1, illustrating a top plan view of the elevator car and the mechanism by which the gates or doors are operated;

Fig. 3 shows an enlarged front elevation of the mechanism mounted in the elevator shaft at each floor for controlling the opening and closing of the doors or gates, with the parts thereon in positions corresponding to the closed positions of the doors;

Fig. 4 is a view similar to that of Fig. 3, showing the parts after they have been moved by the passage of the elevator car to effect a partial opening of the doors at the floor at which this mechanism is located;

Fig. 5 is a transverse section taken on the line 5—5 of Fig. 3;

Fig. 6 is a side elevation of the mechanism illustrated in Fig. 3, showing the mechanism mounted on the wall of the elevator shaft and illustrating the relative position of the actuating member carried by the elevator car before its engagement with said mechanism;

Fig. 7 is an enlarged side elevation of a portion of the mechanism illustrated in Figs. 3 and 6, showing the relative positions of the parts during the movement of one of the operating members by an actuating device carried by the elevator car;

Fig. 8 is a detail section taken on the line 8—8 of Fig. 7;

Fig. 9 is a partial side elevation of the mechanism illustrated in Fig. 3, being similar to the view of Fig. 7, showing the relative positions of the parts as the elevator car leaves the floor at which this mechanism is located and thereby actuates the mechanism to effect the closure of the doors;

Fig. 10 is an enlarged detail section on the line 10—10 of Fig. 7, showing the connection of two relatively movable parts of one of the slidably mounted operating members by which the opening and closing of the doors is controlled;

Fig. 11 shows a vertical section through the elevator shaft and elevator car, illustrating the cable mechanism by which the doors or gates are opened and closed when two oppositely moving doors or gates are employed for each door opening; and

Fig. 12 is a view similar to that of Fig. 11, illustrating the arrangement of the parts when a single door is employed for closing one door opening.

The invention is illustrated in connection with a building having a vertical elevator shaft 15 in which there moves an elevator car 16 with means for stopping the elevator car at the different floors 17. Two door openings 18 are provided on each floor at opposite sides of the elevator shaft 15 and these door openings are bounded at their sides by the side sills 19 and at their upper extremities by the horizontal members 20. In the embodiment shown in Figs. 1 to 11, inclusive, each door opening 18 is adapted to be normally closed by two complementary fire doors 21 which are formed preferably of sheet metal members carried by a frame formed of angle iron members 22.

The two doors 21 which close each door opening 18 are adapted to be moved away from each other until the lower door has its upper edge flush with or below the door sill 17 while the lower edge of 110

the upper door is flush with or above the upper edge 20 of the door opening. The vertical edges of the doors 21 are guided by guide members 23 of Z-bar cross-section which are secured to the 5 side walls 24 of the elevator shaft at opposite sides of the door openings 18.

The elevator car 16 comprises a floor 25 carried by transverse frame members 26 which are connected at their ends to end frame members 27. 10 The floor 25 is carried by upright frame members 28 which are located at the corners of the car and which are united at their upper ends with a rectangular frame composed of transverse frame members 29 and end frame members 30. 15 From the corner of this rectangular frame four diagonal frame members 31 extend inwardly to the center of the car where they are secured to the center block 32. The center block is attached to a cable 33 by which the elevator car 16 is 20 raised and lowered. During the movement of the elevator car, it is guided and maintained out of contact with the walls of the shaft by vertical guide members 34 which are secured to the ends of the elevator car and which have vertical 25 grooves 34^a therein which are engaged by guide rails 35. These guide rails are carried by brackets 36 which are secured to the walls 37 of the elevator shaft. The area of the elevator shaft is somewhat greater than that of the elevator 30 car so that ample space is provided at opposite ends of the elevator car for mounting the mechanism by which the doors 21 are opened and closed.

The operating mechanism for opening the 35 doors or gates at each floor is mounted on the wall of the elevator shaft adjacent that floor and is actuated by a device carried by the elevator car. This mechanism which is mounted in the elevator shaft is illustrated particularly in 40 Figs. 3, 4, 5, 6, 7 and 8, where it is illustrated as comprising a plate 40 which is secured to the end wall 37 of the elevator shaft by studs 41 which pass through blocks 42 by which the plate is spaced from the wall. The plate 40 carries two 45 vertically slidable rack bars 44 each having teeth 44^a and each secured to a plate 44^b which projects laterally from each side of the rack bar to engage one of the under-cut channels 45 which are formed by plates 45^a and 45^b secured to the plate 50 40. The inner plates 45^a are spaced apart and their vertical edges are overlapped by the outer plates 45^b, as shown in Fig. 5, to form the under-cut channels 45. In this way, the rack bars 44 are permitted to slide vertically on the plate and 55 during this movement they are adapted to actuate, or to be actuated by, a pinion 46 the teeth of which mesh with the rack teeth 44^a carried by the rack bars. The pinion 46 is adapted to revolve about a short shaft or bolt 47 projecting 60 from the plate 40 so that the pinion is merely an idler by which motion is transmitted from one rack bar to the other.

The right-hand rack bar 44 has its lower end 65 connected to a cable 48 and the left-hand rack bar has its lower end connected to a cable 49. These cables extend downwardly and are wound in opposite directions around a drum 50 with their other extremities secured to this drum so that when one cable is unwound from the drum, the 70 other cable is wound up thereon. This drum 50 is secured upon a transverse shaft 51 which extends parallel to the under wall 37 of the elevator shaft with its end portion journaled in bearing brackets 52 which are secured on this wall. The ends of 75 the shaft 51 have drums 53 secured thereon and

cables extend from these drums 53 to the elevator doors 21 so that, upon rotation of the shaft 51, the doors are opened or closed, depending upon the direction of rotation. As shown particularly in Figs. 2 and 11, each drum 53 has two cables 54 secured thereto and wound thereon with their free end portions extending upwardly therefrom and over pulleys 55 two of which are mounted on short shafts 56 carried by the end walls 24 of the elevator shaft. One cable 54 is passed over only one of the pulleys 55 while the other cable 54 is extended over both of the pulleys 55 and then these cables are extended downwardly and their extremities are passed through the angle member 22 at the top edge of the uppermost door 21 at each side of the elevator shaft. In addition to the cables 54, each drum 53 has two cables 57 wound thereon in directions opposite to the winding of the cables 54 and the free end portions of these cables 57 are passed over other pulleys 58 mounted on shafts 56 adjacent the pulleys 55. These cables 57 are arranged with one cable passing over one pulley 58 and the other cable passing over both pulleys 58, after which the end portions of the cables are carried downwardly and attached to 100 the angle member 22 forming the upper frame member of the lower door 21 at each side of the elevator shaft. In this way, the rotation of the shaft 51 in one direction is adapted to raise one elevator door and lower the other door at each 105 side of the shaft, while the rotation of the shaft in the opposite direction is adapted to effect the opposite movement of each door. The opening and closing movements of the doors are effected by the actuation of the rack bars 44 and the 110 weight of the doors is counterbalanced by a counterweight 60 which is suspended from a cable 61 through a coil spring 62, as shown in Fig. 11. This cable 61 is wound around the drum 50 previously described and the weight is thereby 115 adapted to counterbalance the weight of the doors.

In order to effect the opening of the doors through the rotation of the shaft 51 and to control the closing movements thereof by the reverse 120 rotation of this shaft, means are provided for actuating the rack bars 44 by the movement of the elevator car 16. For this purpose, the car 16 is provided with a pair of actuating devices 65, shown particularly in Figs. 6, 7, 8 and 9. Each 125 actuating device comprises a roller 66 carried at the end of a plunger 67 which is mounted to reciprocate in a cylinder 68 carried by the elevator car. Each cylinder is provided with threaded end caps 69 which are apertured to receive the plunger 130 67 and each cylinder is secured by U-bolts 70 to angle bars 71 which are secured to one of the frame members 30 at the top of the elevator car by means of bolts 72. The plunger 67 of each actuating device has a coil spring 73 mounted 135 around it within its cylinder 68. One end of the spring engages the cap at one end of the cylinder and the other end of the spring engages a transverse pin 74 having its ends extending through slots 68^a which are formed in the cylinder wall. 140 The springs 73 are compressed so that they normally force the plunger 67 and the rollers 66 toward the rack bars 44.

By reason of the action of the springs 73, the rollers 66 of the actuating devices occupy 145 positions as shown in Figs. 2 and 6, so that as the elevator car 16 approaches the floor adjacent which two of the rack bars 44 are located, the rollers 66 move along paths which bring them into proximity with the front faces of the rack 150

bars when the latter members are reached. Since two rack bars carried by one of the boards normally have an offset relationship, as shown in Fig. 3, the rollers 66 of one actuating device reaches one of the rack bars before the other rack bar is reached by the other actuating device. The result is that the roller 66 of one actuating device moves upwardly until it engages the lug 75 carried by the right-hand rack bar as viewed in Fig. 3. This lug is of rectangular cross-section and projects outwardly from the rack bar in the path of the roller 66 so that when it is engaged by the roller, the right-hand rack bar is moved upwardly and, through the action of the pinion 46, the other rack bar 44 is actuated to move downwardly. As this occurs, the cable 48 connected to the right-hand rack bar rotates the drum 50 and thereby actuates the shaft 51 so that two gates or doors 21 are separated from each other through the operation of the connections previously described. In order to release the roller 66 from engagement with the lug 75 of the rack bar, each rack bar is provided with a releasing plate 77 which is adjustably mounted on the side of the rack bar so that it has a limited relative movement thereon. Each releasing plate is provided with a V-shaped cam projection 77^a which extends outwardly into the path of the adjacent roller 66 and each plate 77 is further provided with a pair of elongated slots 77^b engaged by the studs 78 by which the plate is secured to the rack bar.

The slots 77^b permit a limited longitudinal movement of each plate 77 on its rack bar and, adjacent the ends of the path of travel of the rack bar, the plate 77 is adapted to be engaged by one of two stop members including an upper stop member 79^a and a lower stop member 79^b. These stop members are carried by plates 79 having elongated slots 79^c therein so that they may be clamped in adjusted positions on the plate 40 by means of studs 80. The stop members 79^a and 79^b may thus be spaced apart within a considerable range of adjustment in order to vary the points at which the rollers 66 are released from engagement with the lugs 75 by which the rack bars are moved.

As the right-hand rack bar is moved upwardly by the engagement of one of the rollers 66 with the lug 75 carried by that rack bar, the connected releasing plate 77 moves along with the rack bar until the upper end of the releasing bar engages the stop 79^a at that side of the plate 40, whereupon the motion of the plate 77 is arrested but the rack bar 44 continues to move under the influence of the roller 66 while, at the same time, the roller rides outwardly on one of the inclined faces of the cam projections 77^a, as shown in Fig. 9. The upper stop member 77^a is located so that this action occurs at or adjacent the point where the doors 21 are in their full open positions and upon further movement of the elevator car in the same direction, the roller 66 will ride up on the cam projection 77^a until it passes entirely over the lug 75, thereby releasing the rack bar from the actuating force applied through the device 65 and permitting the right-hand actuating device to continue its travel without actuating the rack bar. During this actuation of the right-hand rack bar, the left-hand rack bar 44 will have been moved downwardly, as illustrated in Fig. 4, until the lower end of the actuating plate 77 carried thereby engages the lower stop member 79^b. Then, as the elevator car continues its upward movement, the roller 66 carried by the

left-hand device 65, will engage the lug 75 on the left-hand rack bar and move it upwardly, thereby actuating the left-hand rack bar to close the doors through the operation of the cable 49 connected to the drum 50, which closing movement is assisted by the action of the counterweight 60.

This closing movement effected through the actuation of the left-hand rack bar continues until the releasing plate 77 carried by this bar engages the upper left-hand stop member 79^a. The roller 66 of the left-hand actuating device then moves upwardly over the cam projection 77^a of this plate and passes over the lug 75 of the left-hand rack bar as the doors 21 reach their closed positions.

The doors then remain closed but are automatically opened again upon downward movement of the elevator by the reversal of the series of operations which has just been described. The left-hand rack bar is then moved downwardly and its motion is transmitted through the pinion 46 to the right-hand rack bar 44 which is thereupon elevated to open the gates through the actuation of the cable 48 connected to the drum 50. When the left-hand rack bar reaches the lower limit of its travel, as determined by the setting of the lower left-hand stop member 79^b, the left-hand roller 56 rides up over the cam projection 77^a of the left-hand actuating plate and thus passes over the projection 75 of that rack bar. Shortly thereafter, the roller 66 carried by the right-hand actuating device engages the lug 75 of the right-hand rack bar which will have been elevated by the previous door opening movement so that the right-hand rack bar is then lowered by the downward movement of the elevator car and this motion is in turn transmitted to the left-hand rack bar which moves upwardly and effects a closing movement of the doors as heretofore described. The downward movement of the right-hand rack bar continues until its releasing plate 77 engages the lower right-hand stop member 79^b, whereupon the further movement of the rack bar causes the roller to ride up over the cam projection 77^a and the lug 75 of the right-hand bar to permit the elevator car to continue its downward movement with the doors 21 restored to their closed positions. In this way, the doors are automatically opened as the car reaches each floor level in either direction of its travel and the doors are automatically closed as the elevator car leaves that floor level in either direction.

In case the elevator car moves upwardly to one floor and then reverses its direction immediately without going beyond that floor, the doors would be automatically closed at the commencement of the downward movement if the stop members were so adjusted on the plate 40 as to cause the right-hand roller 66 to pass beyond the right-hand lug 75 before the floor of the elevator car reached a position flush with the floor level. In that case, the right-hand roller 66 would be above the right lug 75 at the commencement of the downward movement of the elevator car so that the right-hand rack bar would be moved downwardly and thus impart an upward motion to the left-hand rack bar to effect the closing of the doors through the cable 49. By suitably adjusting the stop members 79^a and 79^b on the plate 40, the opening and closing of the doors may be caused to take place at precise determined points in the travel of the elevator car and the extent of opening of the doors may at the same time be exactly regulated.

The apparatus so far described would effect

the automatic closing and opening of the doors at every floor level of a building whether or not any passengers or freight were to be discharged at those floors but, if desired, the operator of the 5 elevator may prevent the opening of the gates or doors at any floor at which the elevator is not going to make a stop by manually withdrawing the plungers 67 of the actuating devices 65 as the elevator car approaches that floor. This is effected by a foot pedal 85 which is pivoted at 86 10 on a bracket 87 secured to the floor 25 of the car. This bracket is connected to an upwardly extending cable 88 which has its upper end attached to one arm of a bell crank lever 89, as shown particularly in Figs. 1, 2 and 11. This bell crank lever 15 has one arm projecting upwardly behind a cross bar 90 having its enlarged ends 90^a slidably engaged by the extremities of the plungers 67 which have enlarged heads 67^a at their ends. When the 20 foot pedal is depressed, the bell crank lever 89 is rocked to move the cross bar 90 inwardly toward the body of the elevator car so that the rollers 66 are both simultaneously withdrawn out of the positions wherein they normally engage 25 the lugs 75 of the rack bars. Inasmuch as the lugs 75 and the cam projections 77^a of both rack bars are so located that they are not both engaged simultaneously by the two rollers 66, the normal 30 operation of the apparatus will not be interfered with by connecting the inner ends of the two plungers 67 together.

In the construction described above, two doors have been employed for closing each door opening but it will, of course, be apparent that a single 35 door may be employed provided the mechanism be arranged so that a greater range of movement is imparted to the door by the actuation of the rack bars. In Fig. 12 of the drawings there is illustrated this modification in which a single 40 door 95 is mounted to slide in guides 96 to close the door opening and this door is connected to two flexible cables 97 which extend upwardly over pulleys 98 and thence downwardly over one of these pulleys and around a drum 99. This drum 45 is mounted on a shaft 101 which corresponds to the shaft 51 previously described, and it is journaled in bearing brackets 102 secured to the side wall of the elevator shaft. The shaft 101 is arranged to be actuated by cables connected to 50 rack bars similar to the rack bars 44 so that when the elevator car approaches the floor at which the door 95 is located, this door is elevated by the rotation of the shaft 101.

Although one form of the invention and a 55 modified construction of the door arrangement have been illustrated and described herein by way of example, it will be understood that the invention may be constructed in various different embodiments coming within the scope of the appended claims.

I claim:

1. The combination with an elevator shaft having a plurality of door openings, of doors for simultaneously closing said openings, an elevator car movable in said shaft, and means actuated by said car for operating said doors to their fully open position as said car reaches a position opposite said door openings, and for positively actuating the closing of said doors as the elevator 70 car recedes from a position opposite said door openings.

2. The combination with an elevator shaft having a number of door openings, of doors for closing said openings, an elevator car movable 75 in said shaft, and means actuated by the move-

ment of said car for automatically and mechanically actuating the opening and closing of said doors as said car approaches and recedes from a position opposite said door openings.

3. The combination with an elevator shaft 80 having door openings, of doors for closing said openings, operating mechanism mounted in said shaft for effecting opening and closing movements of said doors, an elevator car movable in said shaft, and means carried by said car for engaging and operating said mechanism to positively actuate the opening or closing of said doors as said car approaches and recedes from a position opposite said door openings.

4. The combination with an elevator shaft having door openings at different floor levels, of doors for closing said openings, door operating means located in said shaft at each of said floor levels for operating said doors, an elevator car movable in said shaft, and means carried by said car for actuating said door operating means to mechanically and positively actuate the doors to open and closed positions as said car approaches and recedes from the floor level.

5. The combination with an elevator shaft having door openings at different floor levels, of doors for closing said openings, a plurality of door operating means located in said shaft at each of said floor levels for operating said doors, an elevator car movable in said shaft, means carried by said car for actuating either of said door operating means to effect an opening or closing of said doors, and means carried by said car for selectively withdrawing the actuating means from operative engagement with said door operating means.

6. The combination with an elevator shaft having door openings, of doors for closing said openings, an operating member movably mounted in said shaft for positively actuating the opening and closing of said doors, an elevator car movable in said shaft, and means actuated by either the upward or downward movement of said car for moving said member to thereby mechanically control the operation of said doors to either opening or closing positions.

7. The combination with an elevator shaft having door openings at different floor levels, of doors for closing said openings, an elevator car movable in said shaft, an operating member slidably mounted in said shaft and having operating connections to said doors to positively actuate said doors to different open and closed positions dependent upon the position of the elevator car with respect to the floor level, and an actuating member carried by said car for engaging and operating said operating member.

8. The combination with an elevator shaft having door openings, of doors for closing said openings, an elevator car movable in said shaft, operating members slidably mounted in said shaft and having operating connections to said doors, actuating members carried by said car for engaging and operating said operating members the actuation of one of said operating members operating to operate the doors to open position and the actuation of the other of said members operating to operate the doors to closing position, and means for automatically disengaging said actuating member from said operating member after a predetermined movement of said doors.

9. The combination with an elevator shaft having door openings, of doors for closing said openings, an elevator car movable in said shaft, a pair of operating members movably mounted in

- said shaft, means for causing the movement of each operating member in one direction to effect the movement of the other operating member in the opposite direction, one of said operating members controlling the opening movement of said doors, the other of said operating members controlling the closing movement of said doors, actuating mechanism for operating said doors, connections from each of said operating members to 10 said mechanism, actuating devices carried by said elevator car for engaging and moving said operating members during the travel of said car, and means for automatically disengaging said actuating devices from said operating members after 15 predetermined movements of said operating members.
10. The combination with an elevator shaft having door openings, of doors for closing said openings, an elevator car movable in said shaft, 20 a pair of operating members movably mounted in said shaft, means connecting said operating members to effect movement of each member in one direction upon movement of the other in the opposite direction, operating connections from 25 said members to said doors, and actuating devices carried by said elevator car and adapted to engage said operating members to effect movement thereof, the movement of one of said operating members by one of said devices being adapted 30 to open said doors and the movement of the operating member of the other of said devices being adapted to close said doors.
11. The combination with an elevator shaft having door openings, of doors for closing said 35 openings, an operating member movably mounted in said shaft, operating connections from said member to said doors, an elevator car movable in said shaft, an actuating device carried by said car for engaging and moving said operating member, and means movable with said operating member for disengaging said actuating device from said member after a predetermined movement of said doors.
12. The combination with an elevator shaft 40 having door openings, of doors for closing said openings, an operating member movably mounted in said shaft, operating connections from said member to said doors, an elevator car movable in said shaft, an actuating device carried by said car for engaging and moving said operating member, a releasing plate movable with said operating member for releasing said operating member from engagement with said actuating device, and means for limiting the movement of said releasing plate.
13. The combination with an elevator shaft 45 having door openings, of doors for closing said openings, an operating member movably mounted in said shaft, operating connections from said member to said doors, an elevator car movable in said shaft, an actuating device carried by said car for engaging and moving said operating member, a releasing plate movable normally with said operating member and adapted upon relative movement with respect to said member to effect 50 the disengagement of said actuating device from said member, and a stop for arresting the movement of said releasing plate and thereby causing said relative movement under the influence of said actuating device.
14. The combination with an elevator shaft 55 having door openings, of doors for closing said openings, an operating member movably mounted in said shaft, operating connections from said member to said doors, an elevator car movable in said shaft, an actuating device carried by said car for engaging and moving said operating member, a releasing plate movable normally with said operating member and adapted upon relative movement with respect to said member to effect 60 the disengagement of said actuating device from said member, a stop for arresting the movement of said releasing plate and thereby causing said relative movement under the influence of said actuating device.
15. The combination with an elevator shaft 65 having door openings, of doors for closing said openings, an operating member movably mounted in said shaft, operating connections from said member to said doors, an elevator car movable in said shaft, an actuating device carried by said car for engaging and moving said operating member, a releasing plate slidably mounted upon said operating member and normally movable therewith, and a stop for arresting the motion of said releasing plate and thereby causing relative movement of said plate and said operating member under the influence of said actuating device, said releasing plate having a part adapted to engage said actuating device to release said actuating device from said operating member when said relative movement occurs.
16. The combination with an elevator shaft 70 having door openings, of doors for closing said openings, an elevator car movable in said shaft, a pair of operating members slidably mounted in said shaft and having operating connections to said doors, means for effecting movement of one of said operating members in one direction upon movement of the other operating member in the opposite direction, a pair of releasing plates each mounted on one of said operating members for relative movement thereon, a pair of actuating devices carried by said elevator car, a pair of lugs each projecting from one of said operating members in the path of movement of said actuating devices, and a pair of stop members associated with each of said releasing plates for arresting the motion of the releasing plate after a predetermined movement thereof while permitting continued motion of the connected operating member, each of said releasing plates having a projecting part arranged to engage one of said actuating devices and disengage it from the adjacent lug carried by the connected operating member when said releasing plate is arrested by one of said stop members.
17. The combination with an elevator shaft 75 having door openings, of doors for said openings, a car movable in said shaft and having an actuator device, a pair of slideable operating members positively controlling the opening and closing movements of said doors, the actuation of one of said members by said actuator in one line of direction causing an opening of said doors and the actuation of the other of said members in the same line of direction causing a closing of said doors.
18. The combination with an elevator shaft 80 having door openings, an elevator car movable in said shaft, actuating means carried by said car, a pair of operating rack members connected by a pinion adapted to be operated by said actuating means for operating doors to open and close said openings.
19. The combination with an elevator shaft 85 having a door opening, of doors for closing said opening, an elevator car movable in said shaft, and means actuated when said car approaches 90

said opening from either direction for positively opening said doors, said means being adapted to effect a gradual closing of said doors under control of said car as said car recedes from said opening in either direction.

20. In combination with an elevator shaft having a door opening, a door for closing said opening, an elevator car movable in said shaft, and means actuated by said car for operating said door to its fully open position as said car reaches a position opposite said door opening, and for

15. A combination as set forth in claim 10, and for

20. A combination as set forth in claim 10, and for
